UNITED STATES PATENT OFFICE

137,339

DESIGN FOR A COMBINED KNIFE AND PENCIL

Carl Liukko, Tacoma, Wash.

Application November 20, 1943, Serial No. 111,745

Term of patent 14 years

To all whom it may concern:

Be it known that I, Carl Liukko, a citizen of the United States, residing at Tacoma, in the county of Pierce and State of Washington, have invented a new, original, and ornamental Design for a Combined Knife and Pencil, of which the following is a specification, reference being had to the accompanying drawing, forming part thereof.

Figure 1 is a side elevational view of a combined knife and pencil showing my new design, Figure 2 is a top plan view thereof, and Figure 3 is a bottom plan view thereof.

I claim:

The ornamental design for a combined knife and pencil, as shown.

CARL LIUKKO.
